GEORGE EDMUND DONISTHORPE, OF LEEDS, ENGLAND.

Letters Patent No. 82,608, dated September 29, 1868; patented in England, January 21, 1864.

IMPROVED COAL-CUTTING MACHINE.

The Schedule referred to in these Letters Patent and making part of the same.

TO ALL TO WHOM IT MAY CONCERN:

Be it known that I, GEORGE EDMUND DONISTHORPE, of Leeds, in the county of York, England, top and nail-manufacturer, a subject of the Queen of Great Britain, have invented or discovered new and useful "Improvements in Machinery Used in Getting Coal, Stone, and other Minerals;" and I, the said GEORGE EDMUND DONISTHORPE, do hereby declare the nature of the said invention, and in what manner the same is to be performed, to be particularly described and ascertained in and by the following statement thereof; that is to say—

This invention has for its object improvements in machinery used in getting coal, stone, and other minerals. For these purposes, when actuating picks or cutters by engines worked by compressed air or other fluid, I so arrange the picks or cutters and apparatus that two picks or cutters, or two sets of picks or cutters, may be caused by the engine to act alternately.

In order that the compressed air or other fluid may not, as heretofore, at the back or return-stroke be employed to waste, simply acting to bring back the pick or cutter, or set of picks or cutters, and only actuating the pick or cutter, or set of picks or cutters, so as to work when the engine is making its forward stroke, I employ two picks or cutters, or two sets of picks or cutters, receiving motion from the piston of an engine worked by compressed air or other fluid.

The engine is mounted on a suitable truck with the picks or cutters, the piston-rod of the engine gives motion to a lever turning on a centre intermediate of its length, and to the ends of which the two picks or cutters, or the two sets, are respectively attached or connected, so that as one pick or cutter, or one set, acts, the other pick or cutter, or set, retires, consequently the movement of the piston in either direction gives motion to or actuates one cutter or pick, or set, whilst at the same time the other pick or cutter, or set, retires. In place of the trucks on which the engines and picks or cutters are mounted, having flanged wheels, suitable for running on a regular gauge of rails, as is now used in coal-getting machinery, I employ rollers, which will run on rails whether they are laid to a fixed or regulated gauge or not. One rail only acts to guide the truck, and this is laid with care, whilst the other rail on which the truck moves may be out of truth or gauge therewith, and in order that the rail which is laid correctly may be the means of guiding the truck, I apply a clip at each end of the truck, which fits over and partly embraces the head of the rail, the clips being made suitable to slide freely along the rail. On the surface of the guiding-rail, teeth may be formed, to receive a worm or screw, by which the truck is moved, and at the same time the truck is thereby securely retained from moving back during the action of the picks or cutters.

Figure 1 is a side view,

Figure 2 an end view, and

Figure 3 a plan of a machine constructed according to my invention for getting coal, stone, and other minerals.

a a are the side frames of the machine. They are connected together at their ends, and at top and bottom, by the cross-bars *b b*. This frame is carried by the rollers *c c*, the axles of which turn in bearings, *d*, fitted into lugs on the frame.

e e are claws or clips on one of the said frames, embracing the guide-rail *f*. These keep the carriage on the rails, the rollers being made without flanges.

The guide-rail *f* has teeth cut in it, and a worm, *h*, mounted in bearings on one of the side frames, gears therewith. It has a bevelled pinion on its axis, which gears with another bevelled pinion on the vertical axis *i*, having a handle, *i'*, at its upper end, by which it can be turned, and by turning this axis the carriage can be caused to travel either forward or backward.

k is a ram, working in a cylinder, *l*, mounted and secured on the top of the carriage. The compressed air or fluid which works the apparatus can be admitted to this cylinder by a suitable passage and valve, so as to raise the ram. By this means the wheel *m*, which is carried in bearings at the top of the ram, is caused to press

against the roof or top of the working, and the apparatus is thus steadied whilst at work. The ram *k* is made to work air-tight in the cylinder by means of a cup-leather, such as is used in packing hydraulic rams.

Whilst the apparatus is out of work, and the carriage is being taken from place to place, the ram is allowed to descend by cutting off the supply of compressed air or fluid from the cylinder, and opening a passage for the escape of the compressed air or fluid it already contains. The worm *h* can also be raised up out of gear with the rack-teeth on the guide-rail by screwing down the screws *g*. The ends of these screws then press on bars or frames that rest on the top of the bearings of the roller *c*.

n is the cylinder for working the picks or cutters. It has a piston within it, and on the end of the piston-rod the cross-head *o* is fixed, and, from this, connecting-rods or links, *p p*, pass back, and are jointed to the double lever *q q*, which has a strong upright axis, *q'*, at the centre of the carriage, where it is carried in bearings.

The extreme ends of the compound lever *q* carry friction-rollers, *r r*, which lie in recesses made to fit them in the pick or cutter-frames *s s*. These frames are each made with three shelves or brackets, *s' s'*, which may be provided with picks or cutters. The pick-frames are, in order that they may run freely to and fro on the ends of the carriage, supported on a number of friction-rollers, *u u*, mounted on horizontal axes fixed at the top of the carriage. Other pulleys, *v v*, mounted on vertical axes fixed to the pick-frames, keep the said frames steady laterally by running in guide-ways formed for them on the carriage, whilst a third set of pulleys, *w w*, mounted on horizontal axes, keep the pick-frame from rising by bearing on a flange on the carriage, which is immediately over them.

The picks or cutters shown in the drawing are such as I prefer to employ, each pick having combined with it a clearer, *1*, for withdrawing the pieces of coal that are cut away by the pick. Usually when the machine is at work, one shelf or bracket only of each frame is provided with a pick or picks, according to the height at which it is desired to work.

The pick or cutter at the leading end of the machine is, as is shown in the drawings, made shorter than that at the hinder end, so that the latter may serve to deepen the groove cut by the former. The cutter-frame at the hinder end of the machine may have two or more cutters on either of its ledges or shelves, although only one is shown in the drawing. The rearmost cutter is then made of a suitable length to deepen the cut made by the cutter in front of it. Whilst the machine is at work, it is by hand caused to move a short distance after each blow of the rearmost cutter. To do this, the workman, after each alternate movement of the valve-lever, turns the handle *z'*.

The machine is free to move forwards, as each of the rearmost picks is capable of turning on a centre or pin at its rear end, and thus, although the rearmost picks will have just completed their stroke at the time the carriage is to be moved forwards, yet the pick will not prevent the carriage from moving. The turning of the pick on its pin in this manner moves the clearer so as to cause it to enclose the pieces cut away by the pick. The turning of the pick on its centre moves the clearer, by reason of the clearer, which turns on a centre intermediate of its length, being at its end connected by a link to the pick. When the pick has been withdrawn, so as to be clear of the coal, the pick or picks are brought back into their former positions by the spring that is placed between the clearer and the pick. The pick is then ready to make another cut.

In order (when using clearers such as are shown in the drawings) to cause the clearer of the leading pick to enclose the coal or material removed by the pick, the leading pick is by preference to turn on a centre intermediate of its length, and at its rear end has teeth formed upon it, into which a pinion, *2x*, on an axis, *2*, gears. On this axis is an arm, *3*, carrying a pin, *4*. This pin is received in a slot in one arm of the lever *5*. Each time the pick has completed its forward stroke, a roller, *6*, is caused to be moved against the end *5x* of the lever *5*. The lever is thus caused to turn on its centre; this causes the axis *2* also to turn, and so turns the pick on its pin. This movement of the pick, as above described, causes the end of the clearer to be moved towards the pick.

When the pick has completed its backward stroke, another roller, *7*, is brought against the end *5x* of the lever *5*, so moving the lever in the opposite direction, and turning the pick into its original position. The slot in the lever *5* is so formed as not to permit the axis *2* to turn by any strain on the teeth of the pinion upon it.

The axis *2* passes, as is shown, from top to bottom of the machine, and above each of the shelves or brackets of the cutter-frame has a pinion upon it similar to the pinion *2x*, in order that a cutter or cutters on any or all of the shelves may be actuated by it.

The rollers *6*, that give motion to the lever *5*, are carried by a sliding bar, *D*. This sliding bar is pin-jointed to an arm, *9*, on the axis *10*. At the opposite end of the axis is another arm, that is pin-jointed to the lever *z*, that works the valve. The valve may be a slide-valve of ordinary construction, and the workman, by means of the hand-lever *z*, moves it to and fro each time he requires the picks to make a stroke.

The slide-valve is arranged so that compressed air or other fluid for working the engine is only admitted into the cylinder when the valve-lever has been moved to its extreme positions. Thus, the first portion of the movement of the lever-handle always acts first to turn the axis *10*, and when the requisite motion has so been given to the scraper and pick, then air or other fluid is admitted to the cylinder, and the pick is then so caused either to strike a blow or to make its return-stroke.

In place of a lever, *q*, being interposed between the piston-rod of the engine and the picks or cutters, as above described, other mechanical arrangements may be employed to cause the picks or cutters to act alternately, in the manner above explained. Also, the picks or cutters used may be lever-picks, in place of being sliding picks, as they are shown in the drawing, and in this case they may be bolted directly to levers arranged like the levers *q q*. The picks or cutters also, as shown in the drawing, are arranged to work at right angles to the face of the work, but they may be arranged to work at other suitable angles, or the cutters may be caused to move parallel with the work, and cut grooves deeper and deeper therein by being set up after making each cut.

In arranging a machine for making vertical cuts in the work when two picks or cutters, or two sets of

picks or cutters are employed, so as to alternately come into action in the manner herein described, I prefer that the two cutters, or sets of cutters, should be carried by slides, each of which is carried by a separate frame, upon which it is capable of moving upwards or downwards in guides.

The two frames are one above the other, and have a horizontal to-and-fro motion given to them from an engine, in a similar manner to that in which motion is given to the cutter-frames of the machine just described. Suitable mechanism is provided for raising or lowering the slides on the reciprocating frames that carry them.

By these means, when the machine has been placed opposite the face of coal to be cut, and has been set to work, a vertical cut can, by raising or lowering the cutter-slides, be made in the coal, equal in height to the height of the two frames that carry the cutter-slides.

Having thus described the nature of my invention, and the manner of performing the same, I would have it understood that what I claim, is—

1. The so arranging the cutting-apparatus of machines employed in getting coal and other mineral, that two picks or cutters, or two sets of picks or cutters, may be caused by the engine which actuates them to act alternately, so that one pick, or set of picks, may make its forward stroke whilst the other pick, or set of picks, makes its backward stroke, substantially as herein described.

2. The combination, substantially as set forth, with the guiding-rail herein described, of a travelling carriage, provided with clips or guards at each end, to hold it to the rail, and a driving-worm acting on the rail, to propel the carriage, whereby one only of the rails need be laid with care.

3. The combination, substantially as set forth, with the travelling carriage, of a guide-rail, a propelling-worm on the carriage acting on the rail, on clips the carriage embracing the guide-rail, cutting-tools mounted on the carriage, and a pressure-ram, for holding the carriage to its track when working, by pressing against the roof of the mine.

4. The combination, substantially as set forth, with a carriage travelling on ways, and a locking-mechanism for locking the carriage firmly while the cutters are working, of reciprocating cutters arranged on opposite ends of an oscillating arm or lever, vibrating transversely to the line of motion of the carriage, whereby a blow is made at each movement of the piston of the motor, and one cutter may deepen the groove made by the preceding one.

5. The combination, substantially as set forth, with the cutting-tools, of the clearers *i.*, for removing the coal loosened by the cutters.
